[57] CLAIM

The ornamental design for a card holder or similar article, as shown and described.

DESCRIPTION

FIG. 1 is a reduced perspective view of a card holder or similar article showing my new design;

FIG. 2 is an enlarged front elevational view thereof, with the rear being a mirror image and the broken line shown for illustrative purposes only and forming no part of the claimed design;

FIG. 3 is a side elevational view thereof, with the opposite side being a mirror image;

FIG. 4 is a reduced top plan view thereof; and,

FIG. 5 is a reduced bottom plan view thereof.

FIG. 1

FIG. 2

FIG. 3
